LIFESAVING SUIT

Hans Georg Morner, New York, N. Y.

Application November 5, 1942, Serial No. 464,655

1 Claim. (Cl. 2—2.5)

The present invention relates to new and useful improvements in life saving suits.

Objects and advantages of the invention will be set forth in part hereinafter and in part will be obvious herefrom, or may be learned by practice with the invention, the same being realized and attained by means of the instrumentalities and combinations pointed out in the appended claim.

The invention consists in the novel parts, constructions, arrangements, combinations, and improvements herein shown and described.

The accompanying drawing, referred to herein and constituting a part hereof, illustrates one embodiment of the invention, and together with the description, serves to explain the principles of the invention.

Of the drawing:

Figure 1 is a general view showing the suit as worn and ready for maintaining the wearer afloat and dry after he has jumped in the water;

Figure 2 is a fragmentary view with certain parts shown in section and illustrating certain details of construction of the life saving suit;

Figure 3 is a plan view showing the air valve used in the present embodiment; and

Figure 4 is a sectional view taken on line 4—4 of Figure 3.

The present invention has for its object the provision of a novel and improved life saving suit which will protect a seaman and will prevent accidental drowning of an injured seaman who may not be able to assist in righting himself in the water. A further object is the provision of an improved waterproof life saving suit enclosing the body and limbs of the wearer which prevents the trapping of air in the suit as the wearer jumps into the water from a considerable height. Still another object of the invention is to provide a life saving suit which will afford greater protection in various ways to the seaman in emergencies requiring its use.

In accordance with the present preferred and illustrative embodiment of the invention, the life saving suit comprises a waterproof garment having body and limb enclosing portions which are joined together to form a waterproof garment leaving only the face, and some of the head portions exposed, and having a neck portion which is large enough to permit the garment to be donned and yet may be drawn snugly around the neck to render it capable of excluding practically all water even when worn in a rough sea or when the wearer jumps into the sea from a relatively great height. On the upper portion of the garment is provided one or more one-way low pressure valve

means serving to permit the rapid passage of air at a pressure slightly above atmospheric pressure from the interior of the garment and at the same time exclude water from the garment. Thereby, 5 the air within the loose fitting, waterproof garment may be quickly expelled to prevent the possibility of its accumulating at the back of the wearer so as to cause him to be forced forward or face down into the water. The natural buoyancy of the suit is so distributed as to maintain the wearer in an upright position, with his head, and preferably a considerable portion of his shoulders above water even when the wearer is in an unconscious or severely injured condition. 10 Preferably a head covering is permanently attached to the waterproof garment so as to leave only the face of the wearer exposed.

It will be understood that the foregoing general description and the following detailed description as well are exemplary and explanatory of the invention but are not restrictive thereof.

Referring now in detail to the illustrative embodiment of the invention as shown in the accompanying drawing, the garment comprises trouser portions 10 which are permanently attached to the boot or foot portions 12 at their lower end and at their upper end are attached to the relatively loose fitting body portion 14 which extends upwardly to cover the entire torso and is permanently joined to the sleeve or arm-receiving portions 16 having the gloves 18 attached to their lower ends. The trouser, boot, body, sleeve and glove portions are all preferably formed of waterproof material having considerable strength and durability such as heavily rubberized fabric, although these portions may be made of other waterproof material and may differ in shape and form from the showing of the drawing.

To permit the wearer to don the suit easily, 40 the upper portion of the body is relatively large and at the neck is of sufficient size so that the wearer may easily step through the neck portion as the garment is donned. Permanently attached to the neck portion is a neck band 20 formed of 45 relatively soft, pliable rubberized or other waterproof fabric, vulcanized or otherwise permanently attached to the body portion 14 at its upper edge. The neck portion is provided with a draw cord 22 which runs through the hem-like neck band portion 24, and is provided with a slide fastener 26 through which both ends of the cord 22 are passed so that they may be drawn tightly to gather the neck band 20 about the neck of the wearer and beneath his chin. The 50 slide fastener is of any conventional or desired

construction and serves to hold the cord 22 in the tightened position until it is manually released, as by pressure on the release wings 28. The neck portion merges into a head covering portion 30 which is adapted to fit the wearer's head somewhat closely, leaving at least a portion of his face exposed, and may be further provided with a reenforced strap 32 which runs from the junction of the face and neck covering portions at one side, in back of the head and to the other side, thereby relieving the strain at this point.

The garment thus completely encloses the wearer leaving only his face and chin exposed.

Within the garment is contained and permanently attached a sufficient amount of buoyant material such as quilted kapok to provide buoyancy for the wearer and suit, thereby enabling him to float indefinitely regardless of what other garments may be worn beneath the life saving suit, and these buoyant portions are preferably so distributed throughout the interior of the life saving suit that they do not interfere with easy movement of the arms even when the life saving suit is worn over a conventional life saving or kapok jacket. As embodied the quilted kapok portions extend as a wide belt 36 or body encircling member from about the thighs to below the shoulders covering the major portion of the chest, abdomen and back all on the interior of the life saving suit. The belt portion 36 of kapok is permanently and securely attached to the interior of the suit so that it remains in place as the suit is donned.

In order to provide for the easy escape of air from the interior of the suit, even when the wearer is unable to take measures to cause its expulsion, as well as to provide for the ventilation of the interior of the suit under ordinary body movements of the wearer to enable the elimination of body moisture so that the wearer may keep dry over a much longer period of time, one or more one-way low-pressure valve means are provided at the upper portions of the suit, and preferably adjacent the shoulders of the wearer.

As embodied the body portion 14 is apertured at the shoulders and receives in each of the apertures a one-way valve 40, preferably having a disc-like low pressure valve member, which permits the air within the suit to escape and at the same time prevents the entry of water from the outside into the suit. A preferred type of valve is shown in Figures 4 and 5 and comprises a base 42 having an aperture 43 of relatively large size to permit discharge of the air without restriction and a grille cover 44, the base being attached to collar 45 having a turned edge 46 which receives retaining ring 47 by which the valve is securely clamped to the rubberized fabric 46. Within the aperture 43 is a spider 48 having a central headed stud 49 on which is mounted a thin highly flexible rubber disc 50, the edge of which seats against the annular seat surface 51 formed by the outer face of the base to close the aperture 43 which is marginally bounded by said seat surface. A very slight pressure of air on the inner side of the disc 50 slightly above atmospheric pressure or such as caused by voluntary or involuntary body movements of the wearer or pressure of water against the suit will unseat the highly flexible rubber disc to allow the escape of air, while the absence of this pressure will leave the disc 50 seated, thereby effectively preventing the entry of water through the aperture 43 and into the suit.

As the wearer jumps into the water, the pres-

sure of the water against the suit conforms the suit closely to the wearer's body and clothing, and the air freely escapes which would otherwise be trapped and might provide sufficient buoyancy at the wearer's back to force him face down into the water. This is particularly so if he be in an injured or unconscious condition. With the present embodiment, however, the air freely and rapidly escapes so that by the time the wearer has come to the surface, the only buoyancy remaining is the buoyancy of the kapok portions which are so distributed as to maintain the wearer in a normally upright floating condition with his head, and preferably a considerable portion of his shoulders well above the surface of the water.

After the suit is worn in the water for long periods of time, moisture from the wearer's perspiration tends to accumulate within the suit, but the gradual circulation of air through the suit permitted by the cooperation of the neck portion and one-way valves maintains an adequate flow of air to dry this moisture. This circulation of air may be increased by a slight loosening of the neck band so that air is drawn into the suit around the neck, as the person moves in the water and carries on his normal breathing, while this air is expelled through the one-way valve structures which are then above the surface of the water.

My improved construction of suit with its low pressure air vent valve overcomes objections to prior suits which often are of serious character and defeat the purpose for which the suit is designed, namely, the saving of the life of a person who may be forced under an emergency to leave a ship and take to the water. Very often the person who has donned the suit for safety purposes when a ship catches fire, or is torpedoed, or is involved in a collision, or is about to sink from any other cause, may be stunned or injured in the disaster or in jumping from the ship into the water, and may be unconscious or physically unable for a period of time to help himself. Under such conditions when ballooning of the upper portion of the garment occurs due to the presence of air the head of the wearer is liable to be forced face downward into the water. To prevent drowning of the wearer under these conditions the vent valve must be extremely sensitive to air pressure so as to open at once under a slight pressure, such as under the internal pressure of the air itself, the pressure of lapping waves or other movements of the water on the garment or such involuntary body movements of the wearer as may occur. Failure is liable to occur if the valve is one having a restricted passage or is of spring-closed type, or liable to stick or choke or which is of high pressure type, i. e., requires a pressure materially greater than atmospheric pressure to open it. The low-pressure valve which I employ is free from any and all of these objections and will open under the very slightest pressure of the air above atmospheric pressure, such as caused by the pressure of the water against the garment or any movements of the wearer, voluntary or involuntary, which may occur, so that sufficient trapped air will escape to prevent ballooning and to keep the face of the wearer out of the water until he is able to help himself or his rescue takes place. Safety in the use of the garment by a person unable to help himself during this critical period is thus insured.

The invention in its broader aspects is not

limited to the specific mechanisms shown and described but departures may be made therefrom within the scope of the accompanying claim without departing from the principles of the invention and without sacrificing its chief advantages.

What I claim is:

The combination with a life saving suit of waterproof material having body, head and limb inclosing portions and normally open at the neck, with means for securing the garment upon the wearer and closing the open portion thereof tightly about the neck, said portions being joined together to form a waterproof garment and said garment being provided at an uppermost portion thereof with a comparatively large vent aperture, of a quick action vent valve device controlling said aperture and comprising a frame having a base member bearing against one side of the gar-

ment about the vent aperture and formed with an opening conforming substantially in size with the vent aperture, means bearing against the opposite side of the garment and interlocked with and clamping the base member to the garment about the margins of the vent aperture, a spider fixed to the base member, said base member being provided with an annular valve seat concentric with the center of the spider, and an inherently resilient valve disk centrally secured to the spider but being otherwise free and having a peripheral portion engaging and movable toward and from said annular valve seat and being freely flexible so as to open under slight pressure of air within the garment and in the event of ballooning of the upper portion of the garment to allow the confined air to rapidly escape from the garment.

HANS G. MORNER.
